UNITED STATES PATENT OFFICE.

FREDERICK A. HART, OF JERSEY CITY, NEW JERSEY, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,226,072.

Specification of Letters Patent.

Patented May 15, 1917.

Application filed January 6, 1912. Serial No. 669,751.

To all whom it may concern:

Be it known that I, FREDERICK A. HART, a citizen of the United States, residing in Jersey City, in the county of Hudson and State of New Jersey, have invented certain new and useful Improvements in Combined Type-Writing and Computing Machines, of which the following is a specification.

This invention relates to computing machines, such as illustrated in patent to Hanson No. 905,421, dated December 1, 1908, and its object is to provide means for preventing faulty action of the computing mechanism, especially when the same is power driven at high speed.

The improvements relate particularly to the mechanism whereby ten is carried over from any computing wheel to the next higher wheel. In said patent, each computing wheel has a tooth which starts into operation a tens-carrying or carry-over train; and subsequently a power driven set of spurs completes the movements of all the carry-over trains.

In some cases, especially in rapid operation, the carry-over train is liable to be thrown too far by the starting tooth upon the computing wheel. To prevent this, there is provided a stop for every carry-over train; and these stops are retractable automatically to permit the subsequent operation of the spurs which complete the movements of the carry-over trains.

The spurs also are liable, under some circumstances, especially when rapidly rotated, to cause overthrow of the carry-over trains; and to prevent this, there is provided a locking edge upon each of the spurs, which edge temporarily occupies a gap in the mutilated pinion with which the spur meshes, so that said pinion is positively arrested, and hence cannot overthrow.

Other features and advantages will hereinafter appear.

45 In the accompanying drawings,

Figure 1 is a diagrammatic sectional side elevation of a combined typewriting and computing machine of the Underwood-Hanson type, showing the present improvements applied thereto; the parts being in normal positions.

Fig. 2 is a perspective rear view of the lock which prevents overthrow of the carry-over trains when they are started into

action, together with the mechanism where- 55 by the lock is withdrawn; the parts being in normal positions.

Fig. 3 is a sectional side elevation of the computing wheels, tens carrying trains, and spurs for driving the latter; the parts all 60 in normal positions.

Fig. 4 is a sectional rear elevation of the parts seen at Fig. 3.

Fig. 5 is a view similar to Fig. 3, but showing the first lock withdrawn, and the 65 tens-carrying train as being rotated by its driving spur.

Fig. 6 is a view similar to Fig. 5, but showing the movement of the carry-over train as having been completed by said 70 spur; the latter being still in motion, and the locking edge thereon occupying the adjacent gap in the mutilated pinion, whereby overthrow of said pinion is prevented.

Fig. 7 shows the clutch for the spur shaft 75 which drives the carry-over trains.

Numeral keys 1 of the typewriter depress levers 2 to vibrate bell cranks 3, to swing type-bars 4 up to print against a platen 5, which is mounted on a carriage 6. The latter is driven by a spring-barrel 7, and has a rack 8 meshing with a pinion 9, connected to escapement wheel 10, which is controlled by dogs 11; said dogs operated by a universal bar 12, which is driven by heels 13 85 on the type bars.

Said keys 1 have stems 14 to depress arms 15 on rock shafts 16, forming parts of linkages 17, which are depressed by said keys to engage and depress computation pins 18, 90 the latter suitably mounted on bars 19. These bars 19 are elevated one at a time, through the instrumentality of a dog 20 on the carriage 6, said dog engaging jacks 21 one after another, to depress links 22 and 95 vibrate levers 23, which engage linkages 24, to raise the rear ends of said bars 19 *seriatim*.

After the keys 1 have been depressed to print the desired number on the work sheet, 100 the operative pulls forwardly a handle 25, which is provided upon a rock shaft 26, the latter extending across the machine, and having at its ends segments 27, which mesh with idle pinions 28, meshing with opposite 105 racks 29, which form parts of the general operator; said racks connected by cross bars 30, 31.

The forward movement of said handle 25 carries the general operator forward, and cross-bar 30 engages such pins 18 as have been depressed by the keys, and drives forward the bars 19 accordingly; said bars having on their forward ends racks 32 to mesh with pinions 33, which are connected to dial wheels 34; the latter loosely mounted on an arbor 35.

10 The dial wheels are provided with teeth 36 for starting their tens-carrying trains; and each tooth 36, once in each revolution of its wheel, engages one of the teeth in a pinion 37 to start the tens-carrying train, of which said pinion forms a part. This is done while the dial wheel 34 is moving from "9" to "0"; said tooth 36 moving from the dotted-line position to the full-line position at Fig. 3; and the pinion 37 (which has nine teeth) moving one-ninth of a revolution to the Fig. 3 position.

15 Fixed to said pinion 37 is a three-toothed pinion 38, to mesh with a gear 39 provided on the dial wheel 34 of next higher denomination. Each tens-carrying train turns one-third of a revolution at each complete operation thereof; and hence has three normal positions, one of which is seen at Fig. 6.

20 The operation of a tens-carrying train (after the latter has been started by the tooth 36 during the forward stroke of the general operator 29) is completed during the return stroke of said general operator, by one of a set of spurs forming in effect. 25 gears 40, fixed upon a transverse shaft 41, which is driven from the rack 29 through an idle pinion 42, and a pinion 43 meshing therewith and mounted upon shaft 41. Pinion 43 has a clutch connection to said shaft, 30 so as to revolve idly during the forward stroke of the general operator, but to make a complete revolution of the shaft 41 during the return stroke thereof. The clutch connection comprises a ball 44 fitted in a 35 pocket 45 in the shaft, and pressed by a spring 46 into a recess 47 in pinion 43; the ball connecting the pinion and shaft during the return stroke of the pinion, but releasing the shaft during the initial stroke 40 of the pinion.

45 The spurs 40 are placed in spiral or helical order along the shaft 41, so as to operate the ten-carrying trains *seriatim*. When any tens-carrying train is in normal position, Fig. 6, it is inoperable by its spur 40, since the pinion 37 is mutilated, every third tooth being cut away, as at 48, to make a clearance for the spur 40. So long as a tens-carrying train remains in normal position, the shaft 41 may revolve idly with respect thereto. But when a train is started from the Fig. 6 position to the Fig. 3 position, one of the uncut teeth of the pinion moves into the path of its spur 40, and the latter, therefore, at the ensuing movement

of the shaft 41, drives the tens-carrying train and advances the higher dial wheel 34, as at Fig. 5, until the normal position (Fig. 6) is reached; the shaft 41 and all the spurs then completing the revolution to normal position. 70

In order to prevent overthrow of the tens-carrying train when it is started by the tooth 36 on any dial or computing wheel, there is provided an intercepting or stop bar 49, normally in the path of one of the three teeth of pinion 38, as at Figs. 1, 2 and 3; this stop member being placed at such a point as to prevent the tens-carrying train from moving substantially more than one-ninth of a revolution. This stop bar has slots or clearances 50 for the computation racks 32. 75

80 In order to permit movement of the tens-carrying trains to be completed by the associated spur 40, a releasing connection is made between said stop bar 49 and the spur shaft 41, and the bar is made depressible, being arranged to slide down in guideways 51 in end plates 52 of the computing head. Arms 53, pivotally engaging openings or bearings 54 in said intercepting bar, are mounted upon a horizontal rock shaft 55; and from one end of said shaft extends upwardly an arm 56, having at its top a tooth 57 normally seated in a notch 58 in a disk 59, fixed upon the normally stationary spur shaft 41. The leading edge of the notch 58 is inclined to form a cam, and at the beginning of the movement of shaft 41, it acts upon the bevel tooth 57 to cam arm 56 forwardly and the arms 53 downwardly, to depress the bar 49 and the stops thereon out of the paths of all the pinions 38. The bar remains in this position during the passage of the spurs 40 past the tens-carrying trains; and at the latter part of the revolution of the shaft 41, springs 60 lift the bar 49 and snap the tooth 57 into the notch 58 again. Hence the bar 49 is in position to prevent overthrow of any tens-carrying train at the starting movement thereof, but is withdrawn so as to permit the completion of the movement of all the tens-carrying trains that are started. 95 100 105

110 In order to prevent overthrow of the tens-carrying trains when they are revolved by the spurs 40, each spur is provided with a locking rim or edge or broadened tooth 61, one of these being shown in operative position at Fig. 6, in which it will be seen that, 115 as soon as the spur 40 completes the rotation of a tens-carrying train, said locking edge 61 temporarily occupies a gap in the mutilated pinion 37, and hence is in a position to intercept or stop the succeeding tooth of said pinion 37, so that overthrow of the latter is positively prevented; said locking edge 120 being preferably long enough to substantially fill the entire gap made by cutting away a tooth of the pinion at 48 thus formed. 125 130

ag a Geneva lock with said pinion. The spur, as will be seen, has two teeth, and the lower tooth may merge into said locking edge 61 as illustrated, and said edge may be 5 so long that it will remain in the path of the succeeding pinion tooth until possibility of overthrow thereof is eliminated.

By reason of the provision of these locking devices against overthrow, it is also rendered practicable to weaken the springs 62 which connect the detents 63 and 64 for the gears 39 and 37 respectively, so that the computation wheels are operated more easily and quietly.

15 Variations may be resorted to within the scope of the invention; and portions of the improvements may be used without others.

Having thus described my invention, I claim:

20 1. The combination with computation wheels, carry-over trains, said wheels having teeth to start said carry-over trains, and gears to complete the movements of said carry-over trains, of stop devices normally 85 in position to prevent overthrow of said carry-over trains when started by said wheels, and means for automatically withdrawing said stop devices during the operation of said gears.

30 2. The combination with computation wheels, carry-over trains, said wheels having teeth to start said carry-over trains, and gears to complete the movements of said carry-over trains, of stop devices normally 90 in position to prevent overthrow of said carry-over trains when started by said wheels, a rotatable shaft on which said gears are mounted, an actuator on said shaft, and means to enable said actuator to withdraw 95 said stop devices.

3. The combination with computation wheels, carry-over trains, said wheels having teeth to start said carry-over trains, and gears to complete the movements of said 100 carry-over trains, of stop devices normally in position to prevent overthrow of said carry-over trains when started by said wheels, a rotatable shaft on which said gears are mounted, an actuator on said shaft, 105 means to enable said actuator to withdraw said stop devices, and a spring to restore said stop devices to normal positions.

4. The combination with computation wheels, carry-over trains, said wheels having 110 teeth to start said carry-over trains, and gears to complete the movements of said carry-over trains, of a rotatable shaft carrying said gears, a stop bar in position to prevent overthrow of the carry-over trains when started by said wheels, a rock shaft having an arm to withdraw said stop bar, a cam on said gear shaft, a connection from said cam to said rock shaft to withdraw said stop bar at the beginning of the 115 rotation of the gear shaft, and a spring de-

vice to restore the bar and rock shaft to normal positions at the conclusion of the movement of said gear shaft.

5. The combination with computation wheels, carry-over trains, said wheels having teeth to start said carry-over trains, and gears to complete the movements of said 120 carry-over trains, of means to prevent overthrow of the carry-over trains when started by said wheels, and means to release said carry-over trains for actuation by the gears brought into action concomitantly with the movement of said gears.

6. In a computing machine, the combination with computing wheels and numeral keys, of computation members in which numbers are temporarily set up by said keys, a separate device for running said numbers set up into said wheels, a carry-over wheel for each computing wheel but normally disconnected therefrom, means on each computing wheel for giving its carry-over wheel a turn as it is moved by said separate device, a plate normally effective to prevent said turn from being excessive, and means 125 for moving said plate to ineffective position.

7. In a computing machine, the combination with computing wheels and numeral keys, of computation members in which numbers are temporarily set up by said keys, 130 a separate device for running said numbers set up into said wheels, a carry-over wheel for each computing wheel but normally disconnected therefrom, means on each computing wheel for giving its carry-over wheel a turn as it is moved by said separate device in running in numbers, a plate normally effective to prevent said turn from being excessive, means for causing said separate device to give said turned carry-over wheels an additional turn after the computing wheels have been turned by said device, and means for moving said plate to ineffective position by said after-movement of said device.

8. In a computing machine, the combination with a carry-over wheel adapted to be set and later operated, of a stop for arresting it when it is set, and a stop for arresting it when it is operated.

9. In a computing machine, the combination with computing wheels, of carry-over wheels normally ineffective, a device on each computing wheel for moving its carry-over wheel to effective position, a plate arranged to arrest said carry-over wheels at said effective position, a shaft arranged by one rotation to rotate said carry-over wheels to cause the effective wheels to complete the carry-over operation, a cam on the said shaft, and a finger moved by said cam to remove said plate to ineffective position during the rotation of said shaft, but normally allowing said plate to lie in effective position.

10. In a computing machine, the combina-

- 4
- tion with an array of computing wheels, of an array of carry-over wheels, a shaft adjacent to said carry-over wheels, gears spirally arranged on said shaft, a mutilated 5 gear on each carry-over wheel in the spaces between the teeth of which said shaft gears may turn idly, an extension on each shaft gear coöperating with the teeth on each side of said mutilation to positively hold said 10 carry-over wheel against rotation, a tooth on each computing wheel arranged to turn each carry-over wheel so that the remaining teeth in its mutilated gear will be engaged by said shaft gears and the carry-over wheel be 15 turned thereby, means for arresting each carry-over wheel in its effective position, and means for moving said arresting means to ineffective position by the operation of said shaft. 20
11. In a computing machine the combination of a series of carry-over wheels with a series of computing wheels therefor, said carry-over wheels and said computing wheels being normally disengaged, a detent 25 for each carry-over wheel engaging it with a force sufficient only to hold it against displacement when disengaged from its computing wheel, a tooth for each computing wheel for advancing its carry-over wheel 30 while still under the control of its detent and means for positively arresting said carry-over wheel in correct position when so advanced. 35
12. In a computing machine the combination of a series of carry-over wheels with a series of computing wheels therefor, said carry-over wheels and said computing wheels being normally disengaged, a detent for each carry-over wheel engaging it with 40 a force sufficient only to hold it against displacement when disengaged from its computing wheel, a tooth for each computing wheel for advancing its carry-over wheel while still under the control of its detent, 45 means for positively arresting said carry-over wheel in correct position when so advanced, means for engaging the advanced carry-over wheel and moving the same to turn said carry-over wheels against the force 50 of said detent, means to prevent overthrow of said carry-over wheel when moved by said turning means and means brought into action upon movement of said turning means to withdraw the arresting means from said 55 carry-over wheel so that they may be turned to carry. 60
13. In a computing machine, the combination with an array of carry-over wheels, of an array of computing wheels with which they are associated, said carry-over wheels and said computing wheels being normally disengaged, a light detent for each carry-over wheel normally holding it against displacement a tooth on each computing wheel 65 for advancing its carry-over wheel while still under the control of its detent, means for positively arresting said carry-over wheel in correct position when so advanced, a shaft adjacent said carry-over wheel, actuating means on said shaft, arranged to 70 engage said carry-over wheels at their advanced positions and to turn said carry-over wheels, and locking means on said shaft to hold its carry-over wheel locked when turned by said actuating means. 75
14. In a computing machine, the combination with computing wheels and carry-over wheels, of two locks for said carry-over wheels, means normally tending to make one lock effective, means connected to the other 80 lock to move the carry-over wheels, and means for making the first lock ineffective by moving the second lock to operate the carry-over wheels and then lock them. 85
15. In a computing machine, the combination with computing wheels, carry-over wheels for said computing wheels which are preliminarily set by said computing wheels and subsequently operated to carry, an arresting means for each carry-over wheel normally held in position to prevent overthrow of said wheel when preliminarily set, means 90 to complete the turning of said carry-over wheels and a device moved by said turning means to move said lock to ineffective position. 95
16. A computing machine having computing wheels and carry-over wheels, each of which may be set by its corresponding computing wheel; and comprising in combination a lock for preventing the overthrow of said carry-over wheel when being set, and means for afterward completing the turning 100 of the carry-over wheel. 105
17. A computing machine having computing wheels and carry-over wheels, each of which may be set by its corresponding computing wheel; and comprising in combination a lock for preventing overthrow of said carry-over wheel when being set, means for afterward completing the turning of the carry-over wheel, and a lock for preventing overthrow of said carry-over wheel when so turned, the turning of the carry-over wheels acting to withdraw the first lock and 110 render the second lock active. 115
18. A computing machine having computing wheels and carry-over wheels, each of which may be set by its corresponding computing wheel; and comprising in combination a lock for preventing overthrow of each carry-over wheel when being set, means for positively moving said lock to ineffective position, and means for positively turning said carry-over wheel when said lock has 120 been moved to ineffective position. 125
19. A computing machine having computing wheels and carry-over wheels, each of which may be set by its corresponding computing wheel; and comprising in com- 130

bination a lock for preventing overthrow of each carry-over wheel when being set, means for positively moving said lock to ineffective position, and concomitantly positively turning said carry-over wheel to carry, and a lock for preventing overthrow of said carry-over wheel when so turned, brought into action by said moving means.

20. In a computing machine, the combination with computing wheels, of members in which numbers are temporarily set up, carry-over wheels, and means whereby said carry-over wheels are driven both directly and through the computing wheels, said driving means including devices whereby the carry-over wheels are locked against over-throw during the driving action.

21. In a computing machine, the combination with a device in which numbers are temporarily set up, of computing wheels, means for carrying the numbers so set up into said computing wheels, carry-over wheels, means for driving said carry-over wheels, and two kinds of locks for preventing overthrow of said carry-over wheels, brought into action at different times by said driving means.

22. The combination with computing wheels and carry-over trains; detents for yieldingly holding said trains normally ineffective; said wheels having teeth to start said carry-over trains; teeth forming part of said trains to coöperate with said detents, driven gears also coöoperating with said teeth

to complete the movement of said carry-over trains against the action of said detents and to coöperate with said detents in preventing said trains from overthrow after movement by said gears.

23. In a computing machine, the combination with computing wheels and carry-over wheels therefor, which carry-over wheels are preliminarily set by said computing wheels and afterward operated to carry, driving means for said computing wheels and said carry-over wheels, means for interposing a stop so that said carry-over wheels are not overthrown during the preliminary setting thereof by said computing wheels and means for positively arresting said carry-over wheels when completely operated by said driving means.

24. The combination with a carry-over wheel, and means for setting from ineffective to effective position, of means for preventing overthrow of said wheel when so set, an assisting segment for engaging the set carry-over wheel and including an arm having a driving spur and a cam fixed to move with said spur and having a definite relative position with respect thereto and means operated by said cam for moving said overthrow preventing means to ineffective position.
